UNITED STATES PATENT OFFICE.

HUGH W. COLLENDER, OF NEW YORK, N. Y.

BILLIARD-TABLE CUSHION.

SPECIFICATION forming part of Letters Patent No. 275,593, dated April 10, 1883.

Application filed December 29, 1882. (No model.)

To all whom it may concern:

Be it known that I, HUGH W. COLLENDER, of New York city, in the county of New York and State of New York, have invented certain new and useful Improvements in Billiard-Table Cushions; and I do hereby declare that the following is a full, clear, and exact description thereof, reference being had to the accompanying drawings, making part of this application.

My invention relates to new and useful improvements in billiard cushion-strips; and it consists in a rubber cushion-strip having one or more longitudinal holes or cavities running throughout the length of the strip, and having the working face or portion harder or more dense than the perforated body portion.

In another application filed by me simultaneously with this I have shown and described a perforated billiard cushion-strip substantially similar, so far as the feature of having the body of the strip perforated is concerned, with what is shown and described in this application; but in the present case the subject-matter of the invention consists in the combination, with such perforated cushion-strip, of a harder or more dense working-face.

To enable those skilled in the art to make and use my present invention, I will now proceed to more fully describe the same, referring by letters to the accompanying drawings, forming part of this specification, and in which I have illustrated my improved cushion-strip as applied to the cushion-rail of an ordinary billiard-table, and have also shown several modifications of my improvement.

Figure 1 is a sectional view, showing the cushion-strip applied to the cushion-rail. Figs. 2, 3, and 4 are respectively cross-sections (on an increased scale) of my improved cushion-strip under various modifications as to the sizes, number, shapes, and arrangements of the longitudinal perforations; and Fig. 5 is an enlarged view of cushion seen at Fig. 1.

In each figure D is the body portion of the strip, and g the harder or more dense face, while c represents the longitudinal holes or cavities.

The face g of the cushion may be hardened by the incorporation in the rubber strip of canvas or other fibrous material, according to a previous invention of mine, known in the mar-

ket as the "Collender combination-cushion," or said face may be hardened in any other suitable manner or by any other proper means. 55 As shown, the holes or longitudinal perforations of the cushion-body may be made of various shapes and may exist in the cushion-body under various arrangements, the said longitudinal perforations operating, however, in all cases to 60 render the body portion of the cushion capable of being more readily and rapidly compressed or displaced by the force of the blow of the ball, and capable of more readily resuming its former condition, and hence of more rapidly 65 repelling the ball. The hardened face g operates, as usual, to prevent too great embedment of the ball in the face of the cushion, and thus to render the cushion capable of throwing the ball off at angles of reflection more nearly equal 70 to the angles of incidence than would be possible in the use of a rubber cushion-strip having its face equally soft and indentable with the rest of the cushion.

It will be understood that in a cushion-strip 75 thus made with a comparatively hard face, and with the main body portion longitudinally perforated, the said body portion will act more after the fashion of a series of separate springs behind the hard facing than would a body portion made solid, and that by this different sort of action of the body portion the cushion is made "livelier" without any impairment of its capacity to repel the ball at correct angles, while at the same time the cushion-strip will 80 contain less rubber, and consequently can be manufactured and sold cheaper than cushion-strips as now made with hardened faces.

Of course many modifications may be made in the sizes, shapes, and arrangements of the 85 longitudinal perforations and in their relationship to the hardened face of the strip without departing from the spirit of my invention, the gist of which rests in the idea of a rubber cushion-strip having a comparatively hard face and 90 a softer body portion, the springiness of which body portion is augmented by the presence of the longitudinal holes or perforations, in the manner and for the purposes already explained.

I do not therefore wish to be understood as 95 limiting my claim of invention either to any precise shapes or arrangements of the longitudinal perforations or to any precise shape or form of cushion - strip, so long as the cushion

has a comparatively hard face and has its body longitudinally perforated, so that while the face can act in the usual manner it will be backed up by a body portion which will permit the recession of the face portion when struck by the ball, and which will cause said face portion to resume its normal condition more rapidly than in the case of a similarly face-hardened cushion-strip having a solid body portion.

I am aware that prior to my invention billiard cushion-strips have been made which had a hardened face and which also were cored out longitudinally; but in such cushions the internal aperture or hollow space was air-tight, so as to operate with its contents as an air-cushion.

I am also aware that billiard cushion-strips have been heretofore made with a small aperture running longitudinally, which did not act as an air-cushion, and having arranged immediately of the said longitudinal perforation and the soft face of the cushion a metallic strip or

ribbon-like device, as seen, for instance, in the patent of Mayer; but in the last-mentioned construction of cushion there is no such conjoint action between the hardened face and one or more apertures located in rear thereof as is shown and described in my case.

What I therefore claim as new, and desire to secure by Letters Patent, is—

A rubber billiard cushion-strip of diamond shape or triangular in cross-section, having its face or working-surface hardened or rendered more dense than the rest, and formed or provided with an open-ended hole or holes running longitudinally through the cushion, the whole constructed and operating substantially as described, for the purpose set forth.

In testimony whereof I have hereunto set my hand and affixed my seal this 27th day of December, 1882.

HUGH W. COLLENDER. [L. S.]

In presence of—

M. H. SMITH,
A. M. AUSTIN.
